COMBINED PHOTOGRAPHIC COPYING AND VIEWING APPARATUS

Thomas R. Perzentka, Niles, and Stuart C. Plettner,
Evanston, Ill., assignors to Bell & Howell Company,
Chicago, Ill., a corporation of Illinois

Application January 26, 1955, Serial No. 34,240

Term of patent 14 years

(Cl. D61—1)

FIG. 1.

FIG. 2.

Figure 1 is a perspective view of a combined photographic copying and viewing apparatus embodying our new design; and

Figure 2 is a perspective view of the same showing the sides thereof opposite those shown in Figure 1.

We claim:

The ornamental design for a combined photographic copying and viewing apparatus, as shown.
